MACHINE FOR TURNING THE PLATFORM COVERS OF PLATFORM SHOES

Augustus D. Willhauck, Stoneham, Mass., assignor to United Shoe Machinery Corporation, Flemington, N. J., a corporation of New Jersey

Application July 21, 1948, Serial No. 39,876

5 Claims. (Cl. 12—1)

1

This invention relates to machines for turning the platform covers of platform shoes and is herein disclosed as embodied in a machine of the type illustrated and described in United States Letters Patent No. 2,448,102, granted August 31, 1948 on an application filed in the name of Robert H. Lawson. The illustrated machine, like the machine disclosed in the patent to Lawson, just mentioned, is provided with a pair of U-shaped turning tools adapted to fit around the respective ends of an inverted shoe and to engage within the unturned platform cover. The turning operation is performed by urging the shoe downwardly first into one of the U-shaped tools and then into the other tool by means of a plunger operating against the shoe bottom. The action of the plunger is assisted by an auxiliary tool similar to the friction tool disclosed in said Lawson patent.

It is an object of the present invention to provide an improved platform cover turning machine of the type under consideration. In accordance with a feature of the invention, the illustrated machine is provided with means for automatically initiating the actuation of the auxiliary tool operating means at substantially the same instant that the plunger engages the shoe bottom. In accordance with another feature, the illustrated machine is provided with yieldable means for holding the friction tool in engagement with the platform cover during the turning operation. In accordance with still another feature, the illustrated machine is provided with an improved arrangement for so mounting each of the U-shaped turning tools as to enable the tools to flex freely and thereby to accommodate themselves to a wide range of sizes and styles of shoes to be operated upon.

These and other features of the invention are illustrated in the drawings and are hereinafter described and claimed.

Referring to the accompanying drawings,

Fig. 1 is a side elevation, partly in section, showing the operating instrumentalities of an illustrative machine in their initial positions;

Fig. 2 is a view similar to Fig. 1 showing the turning instrumentalities as they engage the shoe and are about to begin the turning operation;

Fig. 3 is a view similar to Fig. 1 showing the turning instrumentalities at an advanced stage of the operation;

Fig. 4 is an angular view, looking down, of the turning instrumentalities and their operating mechanism;

Fig. 5 is a plan view of a toe-turning tool with a narrow-toed shoe mounted thereon;

2

Fig. 6 is a section taken on the line VI—VI of Fig. 5;

Fig. 7 is a plan view of the toe-turning tool with a wide-toe shoe mounted thereon; and

Fig. 8 is a section taken on the line VIII—VIII of Fig. 7.

The platform cover turning instrumentalities of the illustrated machine comprise a heel turning tool 10, a toe turning tool 12 (see Figs. 4 to 8, inclusive), a shoe bottom engaging plunger 14, and an auxiliary tool 16 which operates frictionally against the platform cover to assist the plunger 14 in turning a platform cover C of a partially finished shoe over the tool 10. The partially finished shoe, as shown herein, is mounted on a last L and it has a platform, comprising a midsole M and a wedge heel H.

The supporting structure of the illustrated machine is similar to that disclosed in said Letters

20 Patent No. 2,448,102. It comprises a hollow sheet metal column 18 (Fig. 1) having a rectangular cross section and adapted to rest on the floor, and a head 20 mounted upon the column 18 and consisting of a generally rectangular box-like housing member having a bottom wall or base plate 22. Openings in the walls and top of the head 20 are closed by suitable cover plates, not shown in all of the figures.

The illustrated machine is driven from a motor 24 (Fig. 1) through a belt 26, a clutch 28, and 30 speed reducing gearing 30. The clutch 28, which is normally disengaged, can be engaged to start the operation of the machine by depression of a hand lever 32 (Fig. 4). The clutch mechanism is designed to disengage the clutch 28 and bring 35 the machine automatically to rest at the end of the operation. The effect of the driving mechanism, while the clutch 28 is engaged, is to positively move a slide 34 downwardly in a guideway formed in a post 36, such movement being effected through rack teeth on the slide. Upon disengagement of the clutch 28, the slide 34 is moved

40 up to its initial position by a pair of springs 38, one of which appears in Fig. 1. These springs act upon a rod 40 extending down from the slide 34.

45 A collar 42 adjustably secured upon the rod determines the upward limit of movement of the slide 34. The driving arrangements of the illustrated machine, as above described, from the motor 24 to the slide 34 and including the post 36, springs 38, rod 40, and collar 42, are all similar to corresponding arrangements disclosed in Letters Patent No. 2,448,102, above mentioned, except for the fact that a flexible disk 43 is interposed in the gearing of the illustrated machine

50 to absorb shock.

The plunger 14, as best shown in Fig. 4, is a U-shaped member with a smooth undersurface adapted to bear downwardly upon an end portion of the shoe bottom. It is rigidly secured by a pin 44 (Figs. 1, 2, and 3) to the lower end of a bracket 46. The plunger 14 has an upstanding lug or tongue 43 which fits within a groove formed in the bracket 46 to insure against the turning of the plunger about the pin 44. The bracket 46 is pivotally mounted upon a pin 50 secured between a pair of ears 52 extending forwardly and upwardly from the forward end of a lever arm 54. Journaled in the ears 52 above the pin 50 is a pin 56 (Figs. 2, 3 and 4) having an intermediate eccentric shank portion 58 (Figs. 1 and 4). This eccentric shank portion fits within a groove 59 (Fig. 2) formed in a lug 60 extending upwardly from the bracket 46. The left-hand end of the pin 56, as shown in Fig. 4, is slotted to facilitate the turning of the pin 56 to adjust the angular position of the bracket 46 about the pin 50, thereby adjusting the position of the plunger 14 with accuracy forwardly and rearwardly in relation to the end of the shoe bottom. A set screw 62 (Fig. 4) threaded into one of the ears 52 holds the eccentric pin 56 in an adjusted position.

The arm 54 is integral with and extends forwardly from a hub 64 (Fig. 4) which is rotatably mounted upon a pin 66 secured in lugs 68 formed on the interior surface of the head 20. A link 70 pivotally connected at its lower end to the top of the slide 34 and at its upper end to the arm 54 transmits the operative movements of the slide to the arm. Thus when the clutch is tripped to start the machine through its cycle of operation the slide 34 and with it the arm 54 are positively lowered through the gearing 30 and upon completion of the operation they are automatically raised by the springs 38 to their initial positions.

The friction tool 16, like the corresponding tool disclosed in Letters Patent No. 2,448,102, above mentioned, consists of a plate having a convex working surface upon which are formed upwardly directed teeth which engage the platform cover C and urge it upwardly to facilitate its being turned over either of the U-shaped turning tools. The friction tool 16 (Fig. 1) is mounted indirectly on a substantially horizontal link 72 the forward end of which is pivotally mounted upon a pin 74 carried between the upper ends of a pair of arms 76 and 78. These arms are integral with and extend upwardly from a hub 80 which is freely rotatable upon a pin 82 secured in a boss 84 (Fig. 4) which extends from the interior surface of the head 20. The rear end of the link 72 (Fig. 1) is pivotally mounted upon a pin 86 which is carried between the upper ends of a pair of arms 88. The arms 88 are connected at their mid-portion by a cross bar to form an integral structure shaped like the letter H and their lower ends are mounted upon a pin 90 carried by a post 92 extending upwardly from the base plate 22 of the machine head. The mounting of the link 72, as above described, enables the link to be moved forwardly and rearwardly to bring the friction tool 16 into and out of engagement with a shoe.

Forward movement of the link 72 to bring the friction tool 16 into its operative position is effected by a cam 94 (Fig. 1) which engages a roll 96 freely and idly rotatable upon a pin 98 secured in the arm 76. The cam 94 is formed integrally upon the forward end of an arm 100 which extends forwardly from and is integral with the hub 64. It is evident from the above de-

scription that the arms 54 and 100 are integral with each other and swing as a unit about the pin 66. The operative surface of the cam 94 has a nonconcentric portion or rise 102 which, when the cam descends, urges the roll 96 and, therefore, the link 72 and arm 76 forward. The cam rise 102 merges with a surface 104 which is concentric with the pin 66 and which, therefore, enables the cam to be depressed further without advancing the link 72 beyond its desired operating position. A spring 106 connected at its forward end to the link 72 and at its rear end to the arm 54 at a point adjacent to the hub 64 urges the link 72 rearwardly and holds the roll 96 against the cam 94.

The friction tool 16 has a downward extension 108 (Fig. 1) by which the tool is pivotally mounted upon a pin 110 carried by the forward end of a lever 112 (Figs. 3 and 4) fulcrumed at its intermediate portion upon a pin 114. The link 72 at its forward end has a downward extension 116 which carries the pin 114. Mounted on the lever 112 and surrounding the pin 110 is a torsion spring 118 (Fig. 2) which urges the friction tool 16 in a clockwise direction to hold it against a backing roll 120 (Figs. 1 and 2) indirectly carried by the link 72 as will later be described. The rearward end of the lever 112 carries a roll 122 (Figs. 1 and 3) which can be urged downwardly by a shoulder 124 (Fig. 3) formed on an arcuate sector 126. The roll 122 is normally held up close to the shoulder 124 by a plate 128 which is integral with and which extends laterally and forwardly from the forward end of an arm 130, the rear end of which is mounted for free swinging movement upon the stationary pin 66. The arm 130 is held up by a tension spring 132 the rear end of which is secured to a lug 134 depending from the arm 130 and the forward end of which (not shown) is anchored to the interior of the head 20. A tail 135 (Fig. 1) extending from the sector 126 down below the shoulder 124 maintains a space between the shoulder and the plate 128 into which the roll 122 returns after the sector 126, in descending below the position in which it is shown in Fig. 3, has forced the roll forward beyond the shoulder. When the roll 122 is thus forced forward, during the final portion of the descending operative movement of the sector 126, it rides idly upon a smooth concentric outer surface of the sector.

The upward or operative movement of the friction tool 16 heightwise of the shoe is effected by a downward movement of the sector 126. For guiding the sector in such downward movement a pair of shoulder screws 136 (Fig. 3) engage an arcuate (concentric) slot 138 formed in the sector 126 and coaxial with the pin 66. These screws 136 are threaded into a triangular upstanding bracket 140 having a horizontal flange 142 (Fig. 4) through which the bracket is secured by screws 144 (one of which is shown in Fig. 4) to the link 72. It is evident that, by reason of the construction so far described, the sector 126 is normally held up by the spring 132 as far as permitted by the engagement of the lower end of the slot 138 with the lower screw 136.

The sector 126 is normally disconnected from the operating mechanism and is not connected until about the time that the plunger 14 engages the shoe bottom. In order to effect such engagement, the upper portion of the sector 126 is provided with ratchet teeth 146 which are engageable with complementary teeth formed upon the rear end of a pawl 148. A shoulder screw 150

threaded into the arm 54 engages a guide slot 152 formed in the pawl 148 to guide the movements of the pawl toward and from its engaging and disengaging positions. The forward end of the pawl 148 is pivotally connected by means of a pin 154 (Figs. 1 and 3) to an upstanding arm of a bell crank 156 which is fulcrumed upon the pin 50 and retained thereon by a collar 155. The pin 154 engages a lost motion slot 157 formed in the pawl 148, the forward end of said slot being normally held against the pin 154 by a compression spring 158 housed in a bore in the pawl. A forwardly extending arm of the bell crank 156 is pivotally connected by a pin 160 to a block 162 (Figs. 2 and 4). Extending downwardly from the block 162 through a suitable opening in the bracket 46 is a feeler pin 164 having a reduced lower portion 166 which extends through a hole in the plunger 14 to engage the shoe bottom. A tension spring 168 secured at its lower end by a pin 167 to the bracket 46 and at its upper end to the pin 160 normally holds the feeler pin 164, 166 down to a stop position determined by the engagement of the block 162 with a shoulder on the bracket 46. When the feeler pin 164, 166 is in its lower or stop position the pawl 148 is out of engagement with the sector 126. A nut 165 (Fig. 4) threaded upon the right-hand end of the pin 160 clamps a square block 169, formed on the pin, against the forwardly extending arm of the bell crank 156.

The backing roll 120 is not mounted directly upon the link 72 but is rotatably carried upon a shoulder screw 170 threaded into the lower end of a lever 172 (Figs. 1 and 4). The intermediate portion of the lever 172 is fulcrumed upon a pin 174 (Fig. 3) carried by a plate 176. As best shown in Fig. 4, the plate 176 is somewhat L-shaped, its forward portion being secured by a pair of screws 178 to the forward portion of the link 72. The forward portion of the plate 176 extends laterally from the link 72 and then rearwardly; the link 72 and the plate 176 thus constitute a somewhat U-shaped structure. Secured to the upper end of the lever 172 is the forward end of a tension spring 180, the rear end of which is secured to the forward end of a screw 182 (Fig. 4). The rear portion of the screw 182 extends freely through a hole formed in a lug 184 upstanding from the rear portion of the plate 176. A pair of nuts 186, both threaded on the screw 182 and bearing against opposite sides of the lug 184, hold the screw 182 in an adjusted position. It is evident that the degree of tension of the spring 180 can be adjusted by turning the nuts 186. The spring 180 urges the lever 172 in a clockwise direction (as viewed in Figs. 1, 2 and 3) to press the roll 120 forwardly against a rib 188 (Fig. 1) formed on the rear surface of the friction tool 16. Such movement of the lever 172 about the fulcrum pin 174 is limited by the engagement of the upper portion of the lever with a shoulder 189 (Fig. 2) on the forward portion of the plate 176. The normal or stop position of the roll 120 with respect to the link 72 can be adjusted by loosening the screws 178 and sliding the plate 176 forwardly or rearwardly. Such adjustment is permitted by the provision of a slot 190 formed in the plate 176 to accommodate the screws 178. The forward position of the backing roll 120 should be just about enough to provide for a rearward yielding of the roll to the extent of about $\frac{3}{2}$ of an inch when the link 72 advances and brings the tool 16 into engagement with the platform cover of the shoe.

The turning tools 10 and 12, which are made of spring steel, are carried by a sector-shaped bracket 192 (Fig. 1) which at its lower end is mounted for transverse swinging movement upon a pivot pin 194. Either tool may thus be moved into its operative position while the other tool is moved out of operative position. A safety arm 196 connected to the clutch mechanism prevents tripping of the clutch unless the bracket 192 is in operating position for either of the tools 10 and 12. The pin 194 together with the provisions for securing it to the machine frame, the sector-shaped bracket 192 together with the provisions for operating it and locking it in operating positions, and the safety arm 196 are all similar to corresponding parts of the machine disclosed in said Letters Patent No. 2,448,102. The turning tools 10 and 12, as shown in the drawings, have work-engaging portions similar to although not exactly like the work-engaging portions of the corresponding tools disclosed in the patent just mentioned.

The turning tools 10 and 12 of the machine herein illustrated are not secured rigidly to the sector-shaped bracket 192 but are so mounted thereon as to enable them to conform freely to the shapes of the ends of the shoes to be operated upon. The arrangements for mounting the tools 10 and 12 are similar and the following description will serve for both. Each tool has a generally U-shaped work-engaging portion 198 (see also Figs. 5 to 8 inclusive) comprising a curved rear portion from which a pair of more or less straight arms extend forward. Integral with and depending from each of these arms is a supporting plate 200 in the nature of a leaf spring. A longitudinal slot 202 formed in the intermediate portion of each plate 200 provides for a high degree of flexibility for both bending and torsion. The lower portion of each plate 200 is unslotted and it extends down into a guideway 203 (Figs. 6 and 8) formed in an upstanding lug or supporting bracket 204 integral with a support or holder 206. A shoulder screw 208 prevents longitudinal or heightwise movement of the plate 200 in its guideway and the head of this screw prevents the plate 200 from moving outwardly far enough to become disengaged from the guideway. A limited extent of movement along the shoulder of the screw is permitted as the forwardly extending arms of the work-engaging portion 198 flex toward and from each other. It is evident, therefore, that the plates 200 on each side of the tool 10 (and likewise of the tool 12) are free to move outwardly to accommodate wide heels or toes and to spring inwardly to hold the tool against narrow heels or toes. Not only can the plates 200 yield outwardly along the shoulders of the screws 208, but these plates can also bend and twist in the same manner as the corresponding portions of the tools disclosed in said Letters Patent No. 2,448,102. The form assumed by the tool 12 when engaging a narrow toe is shown in Figs. 5 and 6; the form assumed by this same tool in engaging a wide toe is shown in Figs. 7 and 8. In Fig. 7 the normal form of the tool is indicated by dash lines.

Each of the holders 206 is held against lateral movement by a depending tongue 209 engaging a complementary groove formed in the top of the sector-shaped bracket 192 and is held against forward and rearward movement by means comprising a clamp 210 pivotally mounted upon a pin 212 secured in the bracket 192. Extending up from the clamp 210 are a pair of lugs 214

having undercut beveled surfaces 216 for engagement with complementary beveled surfaces on the holders 206 to prevent disengagement of the forward ends of the holders by heightwise movement. A clamping screw 218 threaded into the bracket 192 and having a hand wheel 220 enables the clamp to be tightened. A compression spring 222 urges the clamp 210 outwardly when the screw is turned to release the holder 206. The rear end of each holder 206 is clamped by the screw 218 against an abutment 223 (Fig. 4) on the bracket 192. This abutment has an undercut recess which engages a tongue on each holder 206 to prevent disengagement of the holder by heightwise movement. This arrangement renders each of the turning tools 10 and 12, together with its holder 206, readily removable and readily replaceable by another tool of different size or shape when wide variations in the sizes or shapes of the shoes to be operated upon are encountered. Notches 224 formed in the abutment 223 cooperate with the safety arm 196 to permit the clutch to be disengaged when one or the other of the tools 10 or 12 is in operating position.

The operation of the machine will now be described. The heel or toe end of the shoe is mounted, in the manner described in Letters Patent No. 2,448,102 already mentioned, upon the appropriate turning tool 10 or 12 and the hand lever 32 is depressed to start the machine upon its cycle of operation. The slide 34 is thus depressed by the gearing 39 to swing the arm 54 downwardly, thereby lowering the plunger 14 and advancing the link 72 to bring the tool 16 yielding into engagement with the platform cover. If the midsole M should extend rearwardly slightly beyond the work engaging portion 198 of the turning tool, the forward thrust of the friction tool 16 will move the shoe forwardly into a suitable position for the turning of the platform cover C. Shortly after the friction tool 16 has thus been advanced into its operating position, the plunger 14 engages the bottom of the platform and by its continued downward movement forces the shoe down, thereby causing the platform cover to be turned over the work-engaging portion 198 of the turning tool. During the idle downward movement of the plunger 14, that is, the movement from the position shown in Fig. 1 to that shown in Fig. 2, the pawl 148 remains disengaged from the ratchet teeth 146 and no upward movement of the friction tool 16 takes place. However, at about the same time as the plunger 14 engages the platform bottom the feeler pin 164, 166 also engages it to cause the pawl 148 to engage the ratchet teeth 146 and thereby move the arcuate sector 126 down. The lever 112 is thus rocked to move the friction tool 16 upwardly and thereby cause it to assist the plunger 14 in turning the platform cover. Fig. 3 shows the positions of the plunger 14 and the friction tool 16 shortly before the turning of the platform cover has been completed. After completion of the turning, the roll 122 will ride idly upon the smooth arcuate surface of the sector 126 while the plunger 14 continues idly to descend until the clutch mechanism automatically disengages to permit the springs 38 to restore the moving parts of the machine to their initial positions.

The smooth under surface of the plunger 14 enables the friction tool 16 to position the shoe forwardly upon the turning tool without interference. While, as appears in Fig. 2, the plunger

14 may not, upon its first contact with the heel bottom, lie flat thereupon, it is evident that before the plunger has descended to the position shown in Fig. 3 the entire under surface of the plunger will engage the heel bottom.

Having thus described my invention, what I claim as new and desire to secure by Letters Patent of the United States is:

1. In a machine for turning the platform covers of platform shoes, a tool adapted to engage within the unturned platform cover of a shoe at one end of the shoe, a plunger engageable with the shoe bottom, means for moving the plunger heightwise of the shoe first into contact with the shoe bottom and then against the shoe bottom to cause the platform cover to be turned over the tool, an auxiliary tool engageable with the platform cover to assist the plunger in turning the platform cover, means for operating said auxiliary tool, and means for automatically initiating the actuation of said auxiliary tool operating means substantially simultaneously with engagement of the plunger with the shoe bottom.

2. In a machine for turning the platform covers of platform shoes, a stationary tool adapted to engage within the unturned platform cover of an inverted shoe at the heel end of the shoe, a plunger engageable with the shoe bottom at the heel end of the shoe, means for depressing the plunger first into contact with the shoe bottom and then further while in such contact to cause the platform cover to be turned over the tool, a friction tool engageable with the platform cover, means for raising the friction tool in frictional engagement with the platform cover to assist the plunger in turning the platform cover, a feeler movable with the plunger and engageable with the shoe bottom, and means responsive to the engagement of the feeler with the shoe bottom for causing said raising means to initiate the operation of the friction tool substantially simultaneously with the contacting of the plunger with the shoe bottom.

3. In a machine for turning the platform covers of platform shoes, a stationary tool adapted to engage within the unturned platform cover of an inverted shoe at the heel end of the shoe, a plunger engageable with the shoe bottom at the heel end of the shoe, means for depressing the plunger first into contact with the shoe bottom and then further while in such contact to cause the platform cover to be turned over the tool, a friction tool engageable with the platform cover, means operated by the plunger depressing means for raising the friction tool in frictional engagement with the platform cover to assist the plunger in turning the platform cover, a connection in said raising means which is initially disengaged to render the raising means inoperative, a feeler movable with the plunger and engageable with the shoe bottom, and means responsive to the engagement of the feeler with the shoe bottom for engaging said connection to render the raising means operative.

4. In a machine having means for turning the platform covers of platform shoes, an auxiliary turning instrumentality comprising a friction tool engageable with the platform cover of a shoe, means for moving said friction tool heightwise of the shoe while in frictional engagement with the cover to assist said turning means in turning the cover and thereby to lessen the strain on the cover as it is being turned, and yieldable means for holding the friction tool in engagement with the cover during the operation.

5. In a machine having means for turning the platform covers of platform shoes, an auxiliary turning instrumentality comprising a friction tool engageable with the platform cover of a shoe to assist said turning means in turning the cover and thereby to lessen the strain on the cover as it is being turned, means for moving said friction tool in a direction tending to turn the cover, a roll engageable with said friction tool, and spring means acting upon said roll to cause the roll to press the friction tool yielding-
ly against the platform cover during the opera-
tive movement of the friction tool.

AUGUSTUS D. WILLHAUCK.
